VENTILATING AND AIR CIRCULATING DEVICE

Filed March 29, 1930

UNITED STATES PATENT OFFICE

2,008,965

VENTILATING AND AIR CIRCULATING
DEVICEAllen O. Miller, Seattle, Wash., assignor to West
Wind Corporation, a corporation of Wash-
ington

Application March 29, 1930, Serial No. 439,924

4 Claims. (Cl. 98—94)

This invention relates to ventilating and air circulating means, and it has reference in particular to a device for that purpose including an electrically driven fan which, in its use as a ventilator for exhausting air from or delivering air into a room, is mounted within a supporting structure or housing which may be placed in a wall of the room, or fitted in a window thereof, and which in its use for circulating air, is removed from and used independently of the housing as the ordinary type of portable, electric fan.

It is an object of the present invention to provide means of the above character in which the fan unit is reversibly insertable within the supporting structure or housing so as to adapt it either for exhausting air from or for driving air into a room, and also to provide the unit with legs, or supports, whereby it may be held in an upright position when used independently of the housing; the legs being foldable or adjustable to a position at which they will not interfere with an easy application of the unit to its housing when it is to be used for ventilating.

Another object of the invention is to provide the housing with a means whereby the fan unit will be held securely in place therein but which may be readily and easily released for removal of the unit.

Other objects of the invention reside in the various details of construction and in the combination of parts and in their mode of operation as will hereinafter be described.

In accomplishing the objects of the invention, I have provided the improved details of construction, the preferred forms of which are illustrated in the accompanying drawing, wherein—

Fig. 1 is a perspective view of ventilating and air circulating device embodying the present invention; showing the fan unit removed from the housing therefor that is fitted within a window opening.

Fig. 2 is a cross sectional view of the fan unit as applied within the housing.

Fig. 3 is a sectional view on the line 3—3 in Fig. 2.

Fig. 4 is a detail of the latch mechanism.

Referring more in detail to the drawing—

The fan unit, in a preferred form of construction, comprises a cylindrical shell 1, open at its opposite ends and there formed with inturned flanges, as at 2, to give stiffness and rigidity to the shell as well as to enhance its appearance.

Fixed within the shell is a diametrically disposed cross bar 3 by which an electric motor 4 is mounted coaxially of the shell and a fan wheel

5 is fixed to the shaft 6 of the motor; the cross bar, motor and fan all being contained within the shell, as shown best in Fig. 2.

Circuit connection wires 8 lead to the motor through an opening 9 in the top wall of the shell and within the cross bar and a switch 10 for controlling the delivery of current is mounted in the lower end portion of the cross bar and this switch is operated by a pull cord 11 that extends from the switch through an opening 12 in 10 the shell directly aligned with the lower end of the cross bar.

For supporting the fan unit in an upright position, I have provided the two rings or legs 13—13. Preferably these parts consist of plates 15 that are pivotally attached as at 14 to flanges 2 of the shell at opposite sides of its base portion and which are adapted to extend laterally and downwardly from the shell to serve as supporting legs, and which are radially curved and may be folded flatly against the shell body which at these places is depressed inwardly, as at 15, to receive them so that when thus folded against the shell, the latter presents a smooth, cylindrical outer surface.

The supporting structure with which the fan unit is to be used may either be permanently mounted within a wall or it may be in the nature of a panel adapted to be fitted in a window opening above or below a sliding window. In Fig. 1, 30 it has been illustrated as a panel for application to a window opening. In this construction the supporting panel is made up of a central section 18 and opposite end sections 18a and 18b that are telescopically connected thereto so as to be 35 adjusted outwardly or inwardly to accommodate windows of different width.

Formed in the central panel 18 is a circular opening 20 and fixed to the panel concentric with this opening, is a cylindrical housing 21 with an 40 inturned peripheral flange 22 at its outer end forming a circular opening 23 which is of the same diameter as the opening 20 and the two are aligned and are adapted to receive the cylindrical shell of the fan unit therein as shown in Fig. 2.

Fixed to and extended inwardly from the inner edges of the flanges 22 and across the bottom edge of the opening 20 is a plate 25 that is provided at its outer end with an upturned abutment flange 26 which serves as a means of limiting outward movement of the fan unit when inserted in the housing. There is also mounted within a slot 27 in the plate, a downwardly yieldable latch plate 28 having a hook portion 29 at its outer end adapted to snap upwardly within openings 30 in 55

the shell to hold the fan unit in place, and against turning in the supporting structure; there are two of the openings 30 and they are so located as to receive the latch hook for reverse positions of the unit.

At the top side of the cylindrical housing 24 a notch 31 is formed in the flange 22 for the passage of the circuit wires 8 when the fan is inserted, and a downwardly facing trough-like plate 32 extends from the notch and beyond the panel 18 and has a downturned abutment 33 which cooperates with the stop 26 to limit inward movement of the fan unit. Likewise, across the base of the housing a slot 34 is depressed in the plate 25 for the passage of the pull cord.

It is also desirable to cover the outer end opening of the housing with a screen 35 to prevent the fan, in operation, from drawing insects or the like into the room. This screen is here shown to be supported along its lower edge in a groove formed at the outer edge of the plate 25 by the spaced flanges 26-26a.

A door 40 is hingedly attached to the inner end of the housing to close the passage when the fan unit is removed.

In using the device for ventilation, the fan unit is inserted within the housing in the manner necessary for obtaining the desired direction of air delivery. For this insertion, the supporting legs 13 are folded against the shell. When the shell is inserted it is held in place by the stops and latch 28. If it is desired to use the fan as a portable unit independent of the housing, it may be withdrawn by depressing the latch and drawing the unit outwardly from the housing. The legs are then adjusted outwardly as in Fig. 1 to support the unit in an upright position.

Supporting housings, as shown in Fig. 1, may be readily applied to various windows either at the top or at the lower end. Housings of a like nature may be built in walls as permanent equipment. One fan may serve a number of these outlets.

An advantage of this particular combination resides in the saving made possible by the portable fan which may be carried from room to room and used where needed, thereby making it unnecessary to provide a fan for each outlet. There is also the advantage that the fan may be reversibly inserted for either drawing air into or from a room. Then there is the advantage in the use of the fan unit independently of the housing.

While I have described quite in detail the construction of the fan and its housing, it is to be understood that I do not wish the claims to be unnecessarily restricted to details but to broadly cover the use of a portable fan that is insertable within its housing in reverse positions in connection with portable panels or permanent fixtures and to be adapted to be withdrawn for use as an independent unit.

In the foregoing matter and in the claims which are to follow, I have used the word "inserted" to differentiate the present fan unit which may be simply slipped into and from its supporting hous-

ing from other fan devices which are placed in position and then secured by means of screws, pivots, or the like, and I have used the word "withdrawn" to differentiate the present fan unit which may be readily removed from its housing by the depressing of a latch from fan devices which are removable only after the removal of screws, or bolts, which are for a more or less permanent mounting. The present construction is featured by its being readily withdrawable from its housing and reversibly insertable, requiring only a few seconds time to withdraw and reverse the position of the fan unit in its housing.

Having thus described my invention, what I claim as new therein and desire to secure by Letters-Patent, is:

1. In combination, a housing formed with an air passage, and a fan unit comprising a shell fitted in said passage and a motor driven fan mounted within the shell for propulsion of air through the passage; said fan unit being removable from the housing and applicable thereto in reverse directions and having supporting legs fixed thereto for functionally supporting the unit in its independent use, and collapsible against the shell for insertion of the unit into the housing.

2. In combination, a ventilating structure applicable to a window or wall opening and formed with a cylindrical air passage, a fan unit comprising a cylindrical shell adapted to fit slidably within the cylindrical passage, a motor driven fan supported within the shell for the propulsion of air therethrough; said shell being removable from and reversibly applicable to the said passage for reversing the direction of the air delivery, a yieldable latch in the housing adapted to interlock with the shell to retain the fan unit in functional position therein, and said fan unit being adapted for use independent of the housing and having means thereon for supporting it functionally when so used and which are collapsible against the shell for insertion of the latter into the housing.

3. In combination, a ventilating structure applicable to a window or wall opening and formed with an air passage, abutment means at one end of the passage, a fan unit removably and reversibly applicable to said passage for propulsion of air therethrough and adapted to engage said abutment means, to limit its outward movement, a yieldable latch mounted by the housing and adapted to lock with the fan unit to hold it against inward movement; said fan unit being removable from the housing for use independently thereof and having laterally extendable means for supporting it functionally when so used.

4. A fan unit comprising a cylindrical shell open at its ends and forming an air passage, a motor driven fan mounted within the shell for propulsion of air through the passage, a pair of plates pivotally fixed to the shell as supporting means for the unit and collapsible against the shell to permit application of the unit within a cylindrical housing of substantially the same diameter as the shell.

ALLEN O. MILLER.
